Primary Examiner — Leanne Was-Englehart*Assistant Examiner* — Alison Davis(74) *Attorney, Agent, or Firm* — SAIDMAN Design Law Group, LLC(57) **CLAIM**

The ornamental design for a peripheral device, as shown and described.

DESCRIPTION

FIG. 1 is a perspective view of a peripheral device showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portions illustrated in dashed broken lines and the portions illustrated within dashed broken lines depict portions of the peripheral device which form no part of the claimed design.

1 Claim, 8 Drawing Sheets(56)
